UNITED STATES PATENT OFFICE.

JULIUS P. BAUMANN, OF NEW YORK, N. Y.

LOOP FOR SHIRTS.

SPECIFICATION forming part of Letters Patent No. 373,918, dated November 29, 1887.

Application filed September 20, 1887. Serial No. 250,167. (No mode¹.)

To all whom it may concern:

Be it known that I, JULIUS P. BAUMANN, of the city, county, and State of New York, have invented certain new and useful Im- 5 provements in Loops for Shirts, &c., of which the following is a specification.

This invention relates to an improved loop for connecting the buttons of the bosoms of flannel shirts, shirt-waists, and similar garments, the loop being very ornamental in appearance and readily applied without tying to the buttons of said shirts.

The invention consists of a loop for flannel-shirt bosoms and the like which is formed 15 of two or more cords that are stitched together parallel to each other and formed by double crossing into looped ends, and an intermediate connecting portion, as will appear more fully hereinafter, and finally be pointed out in 20 the claim.

In the accompanying drawings, Figure 1 represents a front elevation of a flannel shirt with my improved loops. Figs. 2 and 3 are front views of two loops made, respectively, 25 of three and two cords each; and Figs. 4 and 5 are vertical transverse sections respectively on lines *x x* and *y y*, Figs. 2 and 3.

Similar letters of reference indicate corresponding parts.

30 In the drawings, *aa* represent my improved loops, which are used for connecting the buttons of the bosoms of flannel shirts, shirt-waists, and similar garments. Each loop is

made of two or more cords, *bb*, which are arranged sidewise of each other and connected 35 by lateral stitches, the cords being cut off into the proper length required for the loop, and then formed into the required shape by crossing the cords twice and stitching them together at the points of crossing, so that two 40 loop-shaped ends, *dd*, and an intermediate link-shaped connecting portion, *e*, are obtained.

The cords used for making the loops may be of different colors, whereby the ornamental appearance of the same is greatly increased. 45 The looped ends are applied to the buttons of the flannel shirts, as shown in Fig. 1.

The loops are made entirely ready, and are then applied to the buttons of the bosoms in place of the tied lacings heretofore in use. 50

Having thus described my invention, I claim as new and desire to secure by Letters Patent—

A connecting loop for the buttons of flannel-shirt bosoms and the like, composed of cords connected by lateral stitches and crossed in 55 such a manner as to form looped ends and an intermediate connecting portion, the cords forming the loop being fastened at the points of crossing, substantially as set forth.

In testimony that I claim the foregoing as 60 my invention I have signed my name in presence of two subscribing witnesses.

JULIUS P. BAUMANN.
